(57) **CLAIM**

The ornamental design for a storage box for coffee capsules, as shown and described.

DESCRIPTION

FIG. 1 is a top perspective view of a storage box for coffee capsules showing my new design;

FIG. 2 is a top view thereof;

FIG. 3 is a bottom view thereof;

FIG. 4 is a front view thereof;

FIG. 5 is a rear view thereof;

FIG. 6 is a left side view thereof, a right side view being a mirror image of the left side view;

FIG. 7 is a bottom perspective view thereof; and,

FIG. 8 is a perspective view thereof with a drawer pulled. The broken lines depict portions of the storage box that form no part of the claimed design.
